US0D1064000S

(12) **United States Design Patent** (10) **Patent No.:** **US D1,064,000 S**
(45) **Date of Patent:** **** Feb. 25, 2025**

(54) **APPLIANCE UNDER PAN**

(71) Applicant: **Charles B. Hawley, III**, Oak Island, NC (US)

(72) Inventor: **Charles B. Hawley, III**, Oak Island, NC (US)

(**) Term: **15 Years**

(21) Appl. No.: **29/865,791**

(22) Filed: **Aug. 12, 2022**

(51) LOC (15) Cl. **15-07**

(52) U.S. Cl.

USPC **D15/89**; D7/407; D32/55

(57) **CLAIM**

The ornamental design for an appliance under pan as shown and described.

DESCRIPTION

FIG. 1 is a top, front and side perspective view of my new design for an appliance under pan.

FIG. 2 is a top plan view thereof.

FIG. 3 is a bottom plan view thereof.

FIG. 4 is a front elevational view thereof.

FIG. 5 is a rear elevational view thereof.

FIG. 6 is a right-side elevational view thereof; and,

FIG. 7 is a left elevational view thereof.

The portions of the appliance under pan in broken lines form no part of the claimed design.

1 Claim, 5 Drawing Sheets
